BATHTUB

Edward W. Marshall, Chicago, Ill., assignor of thirty-three percent to Anna Marshall and of fifteen percent to Alice Berenice Alexander, both of Chicago, Ill.

Application December 24, 1937, Serial No. 181,509

2 Claims. (Cl. 4—173)

This invention relates to an improved bathtub. After extended use of the customary built-in bathtub, it frequently occurs that the top edge of the tub separates from the wall structure causing a leak between the top edge and the wall, enabling water to seep into the wall and produce damage thereto.

It has been proposed to use attaching brackets and attachments for connecting the top edge of the tub and the wall, to avoid such separation and leakage; but these are objectionable, since they cause added expense in the manufacture and extra work and trouble in the installation, and do not fully solve the difficulty.

15 It is the main object and purpose of this invention to provide a bathtub of the built-in type which comprises in one unitary tub structure all of the essential means necessary for providing a constantly secure and positively leak-proof connection between the upper part of the bathtub and the wall, and thus obviate the necessity of using any separate and additional attaching members.

Another object of this invention is to provide 25 a built-in bathtub having integral flange means at its upper end which is arranged and equipped for conveniently and securely fastening the tub to the wall structure to remain firmly in position; and is also arranged and equipped so as to provide 30 a positively leak-proof bonding connection between the upper part of the tub and the wall.

A further object is to provide such a bathtub with an integral mounting flange which is provided with openings therein for substantially the 35 entire length of the flange, so that fastening elements may be conveniently placed therethru into the upright frame members of the wall, no matter where these members may be located along the flange, and these openings will also serve as 40 anchorage spaces for the finishing material of the wall.

These and various other objects and advantages are attained with this invention, as will become 45 apparent from the following description, taken in connection with the accompanying drawing in which this invention is illustrated in its preferred form of construction; it being understood that various other arrangements and forms of 50 construction may be resorted to for carrying out the objects and purposes of this invention.

In the drawing:

Fig. 1 is a perspective view of a bathtub embodying this invention in its preferred form of 55 construction.

Figs. 2 and 3 are enlarged detail sectional views thereof, taken respectively on lines 2—2 and 3—3 of Fig. 1.

Fig. 4 is a partial sectional view of the tub installed and secured to the vertical frame members of the wall.

Fig. 5 is a partial sectional view, similar to that of Fig. 4, but taken intermediate the frame members.

In the drawing my improved bathtub is illustrated in its preferred form of construction, comprising the customary main portion or body 10 from the upper edge of which extend the ledges or shelf portions substantially horizontally outwards, including the front and rear side ledges 11 and 12, and the two end ledges 13 and 13'. From the front ledge 11 depends the front wall or apron 14, integral therewith and depending down therefrom to the floor.

The rear ledge 12, and also one or both of the end ledges 13 and 13', according to whether one or both of the ends are built into the wall structure, are provided with upwardly extending flanges 16, and 17 and 17', respectively. These upstanding flanges are integral with their respective horizontal ledges 12, and 13 and 13'. Slots 18, and 19 and 19', are provided respectively in said flanges 16, and 17 and 17', and extend horizontally lengthwise thereof. Solid portions or vertical ribs 20 are retained at the corner parts 30 of these flanges, and similar solid portions or ribs 20' are left unslotted between the slots in said flanges, apertures 21 being provided in said solid portion or ribs, as best shown in Fig. 1.

The slots 18, 19 and 19', provide openings along substantially the entire length of the flanges 16, 17 and 17', and more fully so when the apertures 21 are considered in conjunction therewith, wherethru securing elements 22 can be conveniently entered at any desired position along the 40 flanges, so that such securing elements can be readily fastened into the studdings or vertical frame members 23 of the wall structure, as such members are usually spaced from 16 inches to 24 inches apart, and these elements can be conveniently driven into said members no matter where they may be located along the flanges. The securing elements used in the slots are preferably in the form of screws having laterally extending heads 22', as indicated in Fig. 4, so that the heads 50 may be turned horizontally and passed thru the slots if desired. Screws may likewise be extended thru apertures 21, as indicated by the screw 24 in Fig. 5.

It is preferred to provide grooves 25 additional- 55

ly on the lower part of each flange, on the tub-side away from the frame member, and preferably also to provide serrations 26 along said tub-side of each flange, as best shown in Fig. 3. The 5 slots 18, 19 and 19', and the apertures 21, provide openings thru which the finishing material of the wall, for example plaster 27, is extended, as shown in Figs. 4 and 5. This forms a firm bond therewith and provides a secure and positively leak-10 proof connection between the top part of the tub and the material of the wall.

The use of this integral flange means on the tub, with the openings provided thruout the length thereof, and the securing elements fastened therethru directly into the studdings or 15 frame members 23, make a very secure anchorage and support of the tub onto the wall structure which will endure for an extended length of time, and will also prevent any possibility of leak-20 age at this connection.

The tub is constructed of cast iron, sheet steel, and the like; and it is provided with porcelain or 25 enamel on its interior and on the apron and the ledges, in an approved manner, the flanges how-
ever being left uncoated.

I claim:

1. A bathtub consisting of a unitary structure comprising a body portion including ledge means extending horizontally outwardly from its upper 30 end and having flange means extending substantially vertically upwardly from the outer edge thereof, said flange means being provided with

slots extending longitudinally and substantially thruout the length thereof and having solid portions therebetween provided with apertures, said slots and apertures providing openings for receiving securing elements to secure the tub to upright wall members that may be located anywhere along the length of the flange means, said flange means also having groove means provided therein, which with the slots and apertures are adapted to receive the finishing material of the 10 wall to bond the top of the tub securely and leak-proof to the wall.

2. A bathtub consisting of a unitary structure comprising a body portion including ledge means extending substantially horizontally outwardly 15 from its upper end and having flange means extending substantially vertically upwardly from the outer edge thereof, said flange means being provided with slots extending longitudinally for substantially the entire length thereof and having solid portions therebetween provided with apertures, said slots and apertures providing openings for receiving securing elements to conveniently 20 secure the tub to upright frame members that may be located anywhere along the length of the flange means, said flange means also having groove means and serrations provided on the tub-side, which together with the slot means and 25 apertures receive the finishing material of the wall, thereby bonding the tub fully leak-proof to the wall.

EDWARD W. MARSHALL.
